UNITED STATES PATENT OFFICE.

WILLIAM MCCLAVE, OF SCRANTON, PENNSYLVANIA, ASSIGNOR TO MCCLAVE-BROOKS COMPANY, OF SCRANTON, PENNSYLVANIA, A CORPORATION OF PENNSYLVANIA.

FURNACE-GRATE.

1,259,646.

Specification of Letters Patent. Patented Mar. 19, 1918.

Application filed March 23, 1916. Serial No. 86,292.

To all whom it may concern:

Be it known that I, WILLIAM MCCLAVE, a citizen of the United States, residing at Scranton, in the county of Lackawanna and 5 State of Pennsylvania, have invented certain new and useful Improvements in Furnace-Grates; and I do hereby declare the following to be a full, clear, and exact description of the same, reference being had 10 to the accompanying drawings, forming part of this specification.

This invention relates to improvements in furnace grates and the particular object 15 of the invention is the provision of an improved furnace grate for the burning of very small sizes of coal.

In the burning of small size coal, especially grades of anthracite as small as or smaller than what is known as buckwheat, 20 it is absolutely necessary that the draft be equally and uniformly distributed over the entire fuel burning area of the grate to obtain proper combustion of the fuel. The small size of the coal requires the air passages of the grate to be restricted in size 25 and, to obtain a uniform draft throughout the grate, the air passages must be uniform in size and equally distributed. There must be no air passages of substantially larger 30 area than the others, and for this reason, it was long thought that the only successful solution of the air distribution problem was to employ a stationary grate, since in all prior arrangements, the provision of a 35 dumping section resulted in elongated air passages at the joints between adjacent sections, so as to admit blasts of air in large volume at the joints. The elongated air passages allow sifting of the unburned fuel to 40 the bottom of the furnace, resulting in considerable waste, and the large volume of air which finds entrance to the firebed seriously 45 disturbs the fire, so as to make it practically impossible to obtain the best results. The stationary grate, while satisfactory so far as the air distribution is concerned, is very disadvantageous in that it is extremely difficult to clean.

According to the present invention, a 50 novel grate construction is provided, in which a section of the grate, preferably a section intermediate stationary sections, is movable to permit dumping of the fire and cleaning of the grate, and, at the same time 55 the character of the joints between the

dumping section and adjacent stationary sections is such that no elongated air passages or gaps of substantially larger size than the air passages of the grate are formed at the joints and the equal distribution of 60 the draft is preserved throughout the grate.

Other objects of the invention are to generally improve the construction of furnace grates, as will appear from the ensuing detailed description of a structural embodiment of the invention in a preferred form. The novel features of the invention will be pointed out in the claims at the end of the specification.

In the accompanying drawings:

Figure 1 is a longitudinal sectional elevation of a furnace provided with a grate constructed in accordance with the present improvements.

Fig. 2 is a fragmentary plan view on an 75 enlarged scale of the dumping section of the grate and an adjacent stationary section.

Fig. 3 is a section taken transversely of the dumping section of the grate, on the line 3—3 of Fig. 2.

Fig. 4 is a section taken longitudinally of the dumping section of the grate, on the line 4—4 of Fig. 2, the adjacent portions of the front and rear stationary sections being indicated by dotted lines.

Fig. 5 is a transverse section on the line 5—5 of Fig. 1.

Fig. 6 is a transverse section on the line 6—6 of Fig. 1.

Fig. 7 is a fragmentary plan view of the 90 means for tilting the intermediate dumping section of the grate.

Fig. 8 is a plan view on a reduced scale of the interior of a furnace and grate.

Fig. 9 is a fragmentary sectional elevation on an enlarged scale taken on the line 9—9 of Fig. 1 and looking toward the front of the furnace.

Fig. 10 is a longitudinal sectional elevation of one of the stationary bars of the intermediate section of the grate.

Like characters of reference in the several figures indicate the same parts.

In the form illustrated in the accompanying drawings, the furnace is of the battery 105 type, that is to say, the furnace has a series of fireboxes arranged in a line one after the other, the portion of the furnace shown being the firebox at the extreme left hand end of the furnace, and having a front wall 1, 110

a side wall 2, a middle wall 3, separating the firebox from the next adjacent one to the right, and a rear wall 4 connecting the side and middle walls 2 and 3. As shown 5 most clearly in Fig. 8, the front wall 1 of the furnace is provided with feed door openings 5, 5, through which the firebox or inner chamber 6 may be supplied with fuel and a tool inserted to stir the fire. The present 10 invention is, however, in no way concerned with the particular type of furnace illustrated, but in the novel grate construction, and hence it will be understood that the grate may be readily applied to other types 15 of furnaces without departing from the spirit of the invention.

At the front end of the firebox and extending transversely across the front wall 1 is a dead plate 7. The front end of said 20 dead plate rests on an inwardly-projecting ledge carried by the furnace wall 1 and located just beneath the bottom edge of the feed door openings 5, 5, and the sides of the dead plate are formed into projections 25 8 which extend into suitable recesses 9 in the side and middle walls of the furnace and thereby hold said dead plate in place. To permit growth of the dead plate transversely, the recesses 9 in said side and middle walls are deeper than the projections 8. Mounted on the dead plate 7 is a firebrick 30 section 10, the top of which is preferably flush with the bottom edge of the feed door openings 5, 5, as shown in Fig. 1. The rear end of the firebrick section 10 is preferably curved, as at 11, and terminates short of the rear end of the dead plate 7. Mounted on the rear end of the dead plate is a transverse bar 12, the upper surface of which 35 lies somewhat below the top of the dead plate 7, whereby a shelf or ledge is provided for the support of the forward end of the grate, as will hereinafter appear.

Supported in suitable recesses 13 formed 40 in the side and middle walls 2 and 3 of the furnace are transverse bearer bars 14 and 15. The rear end of the dead plate 7 is formed with a depending vertical flange 16, and the forward bearer bar 14 is connected to said 45 depending flange 16 by means of longitudinal strut and tension rods 17. The rods 17 may be adjusted by means of nuts 18, as shown, and serve to prevent the bearer 14 from springing up, when the intermediate 50 dumping section of the grate is tilted, as will hereinafter appear. The rear wall 4 of the furnace is provided with a recess 19 receiving a firebrick section 20, as shown in Fig. 1. At the lower edge of the recess 19, 55 is a transverse bracket bar 21 having forwardly and rearwardly projecting horizontal portions 22 and 23 respectively and a vertical depending portion 24 which may be secured to the inner side of the rear wall 4, 60 in any suitable manner. The rearwardly

projecting portion 23 of the bracket bar 21 projects between the firebrick section 20 and the bottom of the recess 19, and the forwardly projecting portion 22 of the bracket bar supports a transverse bar 25 the upper 70 surface of which is preferably in line with the upper surface of bar 12, said bar 25 forming a shelf or ledge on which is supported the extreme rear end of the grate, as shown in Fig. 1. Connecting the vertical 75 portion 24 of bracket bar 21 and the rear bearer bar 15 are longitudinal adjustable strut and tension rods 26 which assist in maintaining rigidity of the rear bearer bar.

A grate constructed in accordance with 80 the present invention preferably consists of three main sections or divisions, the front section 27, intermediate section 28, and rear section 29. The front and rear separated sections 27, 29, are stationary, front section 85 27 being supported by ledge 12 and forward bearer bar 14, and rear section 29 being supported by ledge 25 and rear bearer bar 15. The upper surfaces of the front and rear ends of the respective front and rear grate 90 sections are downwardly beveled, as shown at 30, the bevels meeting the flat under sides of the grate sections at the extreme ends of the sections. Preferably, the forward end of grate section 27 terminates to 95 the rear of the forward extremity of ledge 12, and similarly the rearward end of grate section 29 terminates in front of the rearward extremity of ledge 25. This construction allows for the normal growth of the 100 sections 27, 29, toward the front and rear walls of the furnace, after prolonged use. Each stationary section of the grate is provided with spaced depending vertical flanges 105 30', running longitudinally of the respective sections, and between adjacent flanges are preferably two longitudinally-extending series of restricted air holes or passages 31, the air holes of one series being staggered 110 with relation to the air holes of the other series. Extending longitudinally between the pairs of series of air passages and on the upper surface of the grate are ribs 32, these ribs being located above the vertical flanges 30', as shown more particularly in Fig. 5. 115

The intermediate dumping section 28 extends transversely of the furnace and is located between the proximate ends of the stationary sections 27, 29, and with its fuel-supporting area or upper surface substantially 120 in the same plane as the fuel supporting areas of the stationary sections. According to the present invention, the intermediate section 28 may be tilted wholly beneath the fuel-supporting areas of the stationary sections, when it is desired to dump the fire and clean the grate, and the joints between the proximate edges of the stationary sections and the dumping section are of such a nature 125 that, while, no interference is offered to the 130

tilting movement of the dumping section, the formation of elongated gaps or air passages is dispensed with, and at the same time, growth of the stationary sections and dumping sections relatively to each other is permitted. As shown, the rearward end of section 27 and the forward end of section 29 are curved or beveled downwardly as at 33, and the said ends of the sections are also curved or beveled upwardly, as at 34. The upper extremity of a curved portion 34 is inwardly offset from the lower extremity of a curved portion 33, and the extremities of said curved portions are connected by a horizontal surface 35. This construction provides overhanging or overlapping edges at the proximate ends of the stationary sections. The opposite transverse edges of the dumping section 28 are curved or beveled downwardly as at 36 and beveled upwardly as at 37, the upper extremities of portions 37 being outwardly offset from the lower extremities of portions 36 and said extremities being connected by horizontal surfaces 37'. The horizontal surfaces 37' are designed to underlap and engage the horizontal surfaces 35 of the respective stationary sections 27 and 29, thereby permitting adjacent edges of the grate to grow toward each other, while at the same time a tight joint is formed, when the parts are in normal position with the intermediate sections bridging the front and rear sections, preventing the entrance of air at the joints. If, however, it be desired to permit the entrance of equally distributed restricted volumes of air at the joints between adjacent edges, so as to preserve the equal distribution of the air throughout the grate, the underlapping edges of the dumping section 28 may be provided with spaced vertical slots 37^a, as shown in Fig. 2. It will be noted that the overhanging edges of the stationary sections cover portions of the slots 37^a, and the said slots will be of such breadth that the uncovered portions of the slots will be of substantially the same size as the air holes in the stationary sections of the grate.

In the present instance, the intermediate dumping section 28 is preferably made up of a plurality of grate bars extending longitudinally of the grate and lying side-by-side. As shown in Figs. 2 and 3, the longitudinal edges 38 of alternate bars 39 are designed to underlap the adjacent longitudinal overhanging edges 40 of the other bars 41, the joints at the proximate longitudinal edges of the bars being similar in construction to the joints at the proximate transverse sides of the dumping section and the stationary sections, whereby growth of the several bars transversely of the grate is permitted. The underlapping longitudinal edges 38 may be also provided with slots 42 similar to the slots 37^a, hereinbefore described. The

fuel supporting area of the bars making up the intermediate dumping section may be reinforced by longitudinally-extending ribs 43, and the bars are provided with series of restricted air holes 44 of the same size and spacing as the air holes in the stationary sections 27, 29. The bars are further reinforced by longitudinal vertical depending flanges 43^a.

The bars of the intermediate dumping section 28 are adapted to be tilted in unison wholly beneath the fuel supporting areas of the front and rear stationary sections 27, 29, by means of the following mechanism: The forward bearer bar 14 is provided with spaced bearing brackets 44' supporting shafts 45 as shown more particularly in Figs. 6 and 7, and the tilting bars are provided with forwardly and downwardly projecting arms 46 mounted on the shafts 45. Two adjacent pairs of bars 39, 41 are mounted by the arms 46 on a single shaft 45, as shown. Rotatably mounted in brackets 49 secured to bearer bar 14 is a transverse shaft 50 having links 51 fixed thereto. The links 51 corresponding in number with the grate bar sections 39, and the free ends of said links are provided with rollers 51^a adapted to engage the central longitudinal flanges 43^b of the respective bars 39. Depending from shaft 50 is a curved link 52, the lower end of which is pivoted to an operating bar 53 extending longitudinally of the furnace and projected through an opening in the front wall thereof. Preferably, operating bar 53 is in two sections adjustably held together by a turnbuckle 54. Pivoted to a bracket 55 supported on the side of the front wall 1 of the furnace is an operating lever 56, and the forward end of the bar 53 is pivoted to said lever.

With the above described construction, if operating lever 56 is pulled outwardly from the furnace, the reciprocatory motion thereby imparted to bar 53 will oscillate shaft 50, in the direction indicated by the curved arrow of Fig. 1. As a result, links 51 will be tilted downwardly in unison, so as to permit the grate bars mounted on shafts 45 to tilt in unison, the central flanges 43^b riding on the rollers 51^a. The tilting of the bars of the dumping section 28 is readily accomplished by reason of the improved construction of the joints hereinbefore described. When the dumping section 28 is shifted back into position wherein the fuel supporting areas of the three sections of the grate are in substantial alinement by moving lever 56 toward the front wall of the furnace, the joints formed between the stationary sections and the dumping section are tight enough to prevent the passage of air, except through the vertical slots hereinbefore described. In the type of furnace illustrated a blast of air is admitted to the

firebox through an opening 57 in the bottom of the furnace.

The grate bars 58, at the extreme sides of the intermediate section of the grate, are 5 preferably not movable, but secured to the bearer bars 14, 15, by front and rear braces 59, 60, as shown in Fig. 10. The forward brace 60 is bolted to the forward bearer bar 14 and the rear brace 59 rests on a ledge 61 10 formed on the rear bearer bar 15. The joints between the stationary bars 58 and the movable bars of the intermediate section are of the hereinbefore described type, with the longitudinal edges of the stationary bars 15 overhanging the proximate longitudinal edges of movable bars. The stationary bars may be set within longitudinally extending recesses 62 formed in the side and middle walls of the furnace, permitting 20 growth of the bars transversely. As shown, the recess in the side wall is somewhat deeper than the recess in the middle wall.

What is claimed is:

25 1. A furnace grate of the class described, comprising front and rear spaced stationary grate sections, each stationary section being provided with an overhanging edge disposed oppositely to the overhanging edge 30 of the other stationary section, and an intermediate dumping section adapted normally to bridge said front and rear stationary sections, said intermediate section being adapted to engage the overhanging edges 35 of the stationary sections, and tiltable on a transverse axis wholly beneath the fuel supporting areas of the stationary sections, and means for so tilting said intermediate dumping section.

40 2. A furnace grate of the class described, comprising front and rear stationary sections, an intermediate dumping section bridging the front and rear sections, said intermediate section being composed of a 45 plurality of separate bars lying side by side and formed with lapping proximate edges, said bars being mounted on a transverse axis relatively to the front and rear stationary sections, and means for tilting said bars 50 in unison beneath the fuel supporting areas of the front and rear sections.

3. A furnace grate such as described, embodying front and rear spaced-apart stationary sections having overhanging proximate edges, an intermediate dumping section having its opposite edges formed to underlap the overhanging edges of the stationary sections, and means for tilting said intermediate section wholly beneath the fuel 55 supporting areas of the stationary sections.

4. A furnace grate such as described, embodying front and rear spaced-apart stationary sections having equally spaced air passages and provided with overhanging proximate edges, an intermediate dumping 60

section having its opposite edges formed to underlap the overhanging edges of the stationary sections, slots in said opposite edges of the intermediate section forming air passages of substantially the same size as the 70 air passages in the stationary sections when the dumping section is in alignment with the latter, and means for tilting the dumping section wholly beneath the fuel supporting areas of the stationary sections. 75

5. A furnace grate such as described, embodying front and rear spaced-apart stationary sections having overhanging proximate edges, an intermediate dumping section adapted normally to bridge said front 80 and rear sections and having its opposite edges formed to underlap and engage the overhanging edges of the stationary sections, a series of air passages in the edges of the intermediate section, and means for 85 tilting the intermediate section wholly beneath the fuel supporting areas of the front and rear sections.

6. A furnace grate such as described, embodying a stationary grate section having its 90 fuel supporting area lying substantially in a horizontal plane and provided with an overhanging edge, a movable grate section having its proximate edge adapted to underlap and engage the overhanging edge of said stationary section and with the fuel supporting area of the movable grate section adapted to lie normally in substantially the same plane as the stationary section, and means for 95 tilting said movable section 100 wholly beneath the fuel supporting area of the stationary section.

7. A furnace grate such as described, embodying a stationary grate section having uniformly spaced air passages of uniform 105 size and an overhanging edge, a movable grate section having its proximate edge formed to underlap and engage the overhanging edge of said stationary section, the edge of the movable section having spaced-apart slots of dimensions to form air 110 passages substantially uniform in size with the air passages in the stationary section, and means for tilting the movable section wholly beneath the fuel supporting area of the 115 stationary section.

8. The combination with a furnace, front and rear stationary grate sections having their oppositely disposed edges spaced to form an intermediate dumping outlet, means 120 for supporting the front and rear ends of said stationary grate sections, intermediate transverse bearer bars supporting the stationary sections beneath the fuel supporting areas of the latter and with the oppositely 125 disposed edges of the front and rear sections extending respectively rearwardly and forwardly of the transverse bearer bars, an intermediate dumping section adapted normally to engage the extending edges of 130

the stationary sections beneath the fuel supporting area of the latter and thereby adapted to bridge the intermediate dumping outlet, and means for tilting said intermediate dumping section about a transverse axis relatively to the front and rear stationary sections.

9. The combination with a furnace having transverse supporting ledges projecting inwardly from the front and rear walls thereof, of front and rear stationary grate sections having their proximate edges spaced apart to form an intermediate dumping outlet, and their front and rear edges overhanging said transverse supporting ledges, transverse bearer bars supporting the stationary sections beneath the fuel supporting areas of the stationary sections and with the proximate ends of the front and rear sections extending respectively rearwardly and forwardly of the transverse bearer bars, an intermediate dumping section adapted normally to engage the proximate ends of the stationary sections to bridge the intermediate dumping outlet, and means for tilting said intermediate dumping sections about a transverse axis.

10. The combination with a furnace, of a grate embodying front and rear spaced-

30 apart stationary sections having their respective front and rear ends supported by the front and rear walls of the furnace, transverse bearer bars supporting the stationary sections adjacent the proximate ends of the latter, an intermediate grate section composed of a plurality of tilttable grate bars and stationary bars at the sides of the tilttable bars mounted on the transverse bearer bars and parallel with the side walls of the furnace, and means for moving the tilttable 35 bars in unison about a transverse axis.

11. The combination with a furnace, of a grate embodying front and rear spaced-apart staticnary sections having their respective front and rear ends supported by 40 the front and rear walls of the furnace, transverse bearer bars supporting the stationary sections adjacent the proximate ends of the latter, an intermediate grate section composed of a plurality of tilttable grate bars 45 and stationary bars at the sides of the tilttable bars mounted on the transverse bearer bars and parallel with the side walls of the furnace, and means for moving the tilttable bars in unison about a transverse axis and 50 wholly beneath the fuel-supporting areas of the stationary sections.
